UNITED STATES PATENT OFFICE.

JAMES I. FLANAGEN, OF PHILADELPHIA, PENNSYLVANIA.

DESIGN FOR A PIPE-COLLAR AND FLUE-STOPPER.

SPECIFICATION forming part of Design No. 19,006, dated April 9, 1889.

Application filed December 3, 1888. Serial No. 292,535. Term of patent 7 years.

To all whom it may concern:

Be it known that I, JAMES I. FLANAGEN, a citizen of the United States, residing in the city and county of Philadelphia, State of Pennsylvania, have invented and produced a new and original Design for a Flue Stopper and Collar, of which the following is a specification, reference being had to the accompanying drawing, forming part thereof.

The leading feature of my design for a flue stopper and collar is a breast having thereon a row of scroll-shaped figures.

In the drawing, 1 represents scroll-shaped figures on the breast of a flue stopper and collar. 2 represents an inner circular rim or

bead encircling a central field, 4, and 3 represents an outer rim or bead encircling said figures. The scroll-shaped figures are shown as extending radially on the breast and entirely around the same.

What I claim is—

The design for a flue stopper and collar herein described, consisting of a central field, a rim surrounding said field, a breast with scroll-shaped figures thereon, and an outer rim, substantially as shown and described.

JAMES I. FLANAGEN.
